UNITED STATES PATENT OFFICE.

WALTER WILLIAM COLLEY, OF LONDON, ENGLAND.

MACHINE FOR CRAPING PAPER.

1,411,656.

Specification of Letters Patent. Patented Apr. 4, 1922.

Application filed May 14, 1920. Serial No. 381,284.

To all whom it may concern:

Be it known that I, WALTER WILLIAM COLLEY, managing director of Colley's Limited, roll-paper manufacturers, of 3 to 12 Marine Street, Bermondsey, London, S. E., 16, England, a subject of the King of Great Britain, have invented certain new and useful Improvements in Machines for Craping Paper, of which the following is a specification.

10 This invention relates to improvements in apparatus for craping paper in the form of a continuous web, and has for its primary object to provide a craping machine adapted to effect the craping operation upon 15 two or more layers of paper simultaneously, or upon paper of greater thickness than has heretofore been dealt with, and to permit of the craped paper being delivered from the machine in the form either of separated 20 layers or of a single layer which, if more than one layer of paper has been fed to the machine, will be composed of two or more thicknesses permanently united to one another as the result of the craping operation. 25 A further object of the improvements is to enable the paper, before leaving the machine, to be if desired impressed with transverse lines of weakness, or longitudinally divided, or both.

30 According to the present invention there is employed in combination with a pair of craping rollers having respectively a smooth and rigid and a relatively soft and resilient peripheral surface, an "obstructor" constituted by a straight-edged flat blade so mounted as to present its edge between the surfaces of the craping rollers at or near their line of bite. The paper is drawn forward by contact with the surface of the rigid 35 roller and carried thence at such a rate through between the edge of the obstructor-blade and the contiguous surface of the soft and resilient roller, that the paper, owing to its advance being momentarily checked at 40 short intervals, is alternately crowded-up against and allowed to pass the opposed edge of the obstructor; the crowded-up portions of the paper forming crape-like creases or wrinkles which are rendered permanent by 45 their immediately subsequent passage, in the folded state, between the obstructor and the soft and resilient roller.

This arrangement obviates the necessity of damping the paper, as has been proposed 50 in cases where the rigid and resilient rollers have served not as craping rollers (properly

so called) but as a means of squeezing out excessive moisture from the paper and flattening it against the surface of the rigid roller, from which the paper has been subsequently removed in a crinkled condition by the action of a "doctor" constituted by a blade resting upon the surface of the rigid roller at a distance beyond the line of bite between the two rollers.

60

65

The several layers of paper are drawn continuously from one or more suitably-braked supply-reels mounted at the feed end of the machine, and are led over guide-rollers so as to enter together, in mutual superposition, 70 between the craping rollers, whence the layers are led together over a positively-driven take-off roller with which each delivery-reel for the reception of a separate layer of paper contacts in such manner as to 75 be continuously driven by frictional contact therewith, the journals of each delivery-reel being guided radially of the take-off roller so as to be free to recede from the axis of 80 the latter as the thickness of paper wound upon the delivery-reel increases.

75

If it is required to produce transverse lines of weakness in the paper at predetermined intervals in its length, the layers of paper, before being separated from one another, are led together between a pair of positively-driven rollers whereof one (preferably the upper roller) carries a radially-projecting knife (or knives) or row of pins extending parallel to the axis of the roller, 90 whilst the other has a countersunk strip of soft metal or other suitable material, or a row of holes, adapted to coact with the edge of the knife or the points of the pins, so that the layers of paper, as they pass together between these rollers, will be transversely slitted or perforated at predetermined intervals in their length.

95

If the paper is required to be longitudinally divided into separate strips, the layers of paper, before being separated from one another, but after receiving transverse lines of weakness if such be impressed upon the layers, are led together between a pair of positively-driven rollers whereof one 100 (preferably the smaller roller) carries a series of circumferentially-projecting annular knives spaced apart at distances corresponding to the widths of the strips whilst the other roller (preferably of considerably 105 large diameter) presents a similar series of grooves adapted to coact with the knives

100

105

110

in slitting lengthwise through all the layers of paper at once and continuously. This last mentioned grooved roller may serve as the take-off roller previously referred to.

5 In the accompanying drawings, which illustrate one form of the invention, Figure 1 is a side elevation, partly in longitudinal vertical section, of a paper-craping machine embodying the improvements; and Figure 2 10 is a plan view of that portion of the machine which includes the craping, perforating, and slitting rollers, the delivery-reels being removed for the sake of clearness. Figure 15 3 shows diagrammatically, the train of gear-wheels through which the several rollers are driven.

In the example illustrated, which shows a convenient construction of machine for craping, transversely weakening, and longitudinally dividing two layers of paper at one 20 operation continuously, 11 and 12 are the supply reels mounted one above the other in bearings 13 and 14 at the feed end of the machine; the reels, which are free to revolve 25 as the respective webs 15 and 16 of paper are drawn from them, being adapted to be braked by means of levers 17 and 18 pivoted to the frame of the machine and provided with adjustable weights 19 and 20 for regulating 30 the pressure exerted by the levers upon the reels.

The web of paper 15 drawn from the upper reel 11 is led direct to a guide-roller 21 to which the web 16 drawn from the lower 35 reel 12 is also led after passing beneath another guide-roller 22, and the now superposed webs are led together over a further guide-roller 23, after leaving which the superposed webs pass between the upper and 40 lower craping rollers 24 and 25. Of these craping rollers, the lower one 25 has a smooth and rigid surface, whilst the upper roller 24 has a soft and resilient surface due to the core of the roller being peripherally 45 covered, as indicated, with rubber, felt, or other suitable material. The lower craping roller 25 revolves in stationary bearings, whereas the bearings of the upper craping roller 24 are movable in vertical guides are 50 pressed upon by springs (not shown) the stress of which is capable of being regulated at will by means of adjustable screws as indicated at 26.

The "obstructor" 27 is a straight edged 55 flat blade of metal of a thickness corresponding with the character of the craping required, adjustably fixed so as to extend substantially in the plane of the tangent to the surfaces of both craping rollers 24 and 25 at 60 their line of bite; the edge of the blade being square or blunt and presented in such position as to be encountered by the paper as it passes between the craping rollers. The obstructor blade 27 may be supported on 65 brackets on the side frames of the machine as

indicated at 28, so as to be adjustable in the direction of the tangent to both rollers 24 and 25 at their line of bite; set-screws being passed through holes in the brackets so as to bear against the blade near its rear edge.

70

After submission to the craping operation, the superposed layers of paper are led together between a pair of positively-driven perforating-rollers 29 and 30 whereof the upper roller 29 carries a straight row of 75 radially-projecting pins 31 arranged in several series (five are shown in the example) corresponding in position and extent, lengthwise of the roller, to the widths of the respective strips into which the conjoint web 80 of paper is to be subsequently divided as hereinafter explained; whilst the lower roller 30 is formed with a corresponding row of holes adapted to coact with the pins 31 in effecting the piercing of the paper.

85

On leaving the perforating-rollers 29, 30, the conjoint web of paper is led between a pair of positively-driven slitting rollers 32, 33, whereof the upper roller 32 is of relatively greater diameter and has its surface peripherally grooved as at 34 at intervals, lengthwise of the roller, corresponding to the widths of the respective strips into which the web of paper is to be divided; whilst the lower roller 33, which is of relatively smaller diameter, carries a series of circumferentially-projecting annular knives 35 spaced apart at intervals corresponding to the positions of the grooves 34; the revolving knives 35 and grooves 34 being 100 adapted to coact with one another in continuously slitting the web of paper in the direction of its length so as to divide it into the required number of separate strips.

95

The paper passes in contact with the lower side of the grooved slitting-roller 32, which serves as a take-off roller, and is then led upwards over the surface of this roller; the two layers 15 and 16, which are separated from one another after undergoing the slitting operation, being respectively wound upon delivery-reels 36 and 37. Each of these 105 reels is driven, not positively, but by frictional contact between the outermost convolution of paper wound upon it and the bare surface of the roller 32; the bearings of the respective reels 36 and 37 being free to recede, along guides 38 and 39, from the axis of the roller 32 as the thickness of paper wound upon each reel gradually increases.

110

In cases where transverse weakening and longitudinal division of the conjoint web of paper are not required, the pin-carrying roller 29 and the knife-carrying roller 33 are withdrawn from the machine.

115

In the example described above, it is assumed that the superposed layers 15 and 16 forming the conjoint web of paper, after being subjected to the craping, transverse weakening, and longitudinal slitting opera-

120

125

130

tions, are required to be separated from one another before final delivery. But, inasmuch as the craping operation has for effect to unite the layers of paper so closely that they are not liable to become accidentally separated from one another, it is evident that such a machine may be employed for producing what may be termed a composite or duplex (or it may be a multiplex) craped paper comprising two (or more) layers thus united, only a single delivery-reel 36 or 37 in such case being required.

In any case, the employment of separate supply-reels (such as those shown at 11 and 12) for the respective layers of paper is not essential, as it may sometimes be found convenient to wind the several layers initially in mutual superposition upon, say, a single reel whence the conjoint web of paper is drawn as if it comprised only a single layer.

The method of driving the several rollers of the machine shown in Figures 1 and 2 is illustrated diagrammatically in Figure 3, wherein 38 is a rotary shaft carrying fast-and-loose belt pulleys 39, 40 (Figure 2) for enabling the shaft to be driven or stopped at will in the well-known manner. Fast upon the shaft 38 is a spur-wheel 41 which gears with a spur-wheel 25^b fast on the arbor 25^a of the lower craping-roller 25, this wheel 25^b in turn gearing with a spur-wheel 24^b of equal diameter fast on the arbor 24^a of the upper craping roller 24. The wheel 41 also gears, through an idle wheel 42, with a spur-wheel 30^b fast on the arbor 30^a of the lower perforating-roller 30, this wheel 30^b in turn gearing with a spur-wheel 29^b of equal diameter fast on the arbor 29^a of the upper perforating roller 29. The wheel 41 further gears, through an idle wheel 43, with a spur-wheel 32^b fast on the arbor 32^a of the grooved slitting-roller 32, a duplicate of this wheel 32^b (but placed at

the opposite end of the arbor 32^a) in turn gearing with a spur-wheel 33^b of relatively 45 smaller diameter fast on the arbor 33^a of the knife roller 33. By the arrangement just described, all the rollers are positively driven in the proper directions, the diameters of the respective spur-wheels being proportioned in accordance with the peripheral velocities required in the several rollers themselves.

I claim:—

1. In a paper-craping machine, the combination with a pair of craping rollers having respectively a smooth and rigid and a relatively soft and resilient peripheral surface, of an "obstructor" constituted by a straight-edged flat blade so mounted in the machine 55 as to present its edge between the surfaces of the craping rollers at or near their line of bite, substantially as and for the purpose set forth.

2. In a paper-craping machine as claimed 65 in claim 1, a pair of coating rollers between which the paper, after subjection to the craping operation, is led; said rollers being provided with means for producing transverse lines of weakness in the paper at predetermined intervals in its length, substantially as set forth.

3. In a paper-craping machine as claimed in either of the preceding claims, a pair of coating rollers between which the paper, 75 after subjection to the craping operation, is led; said rollers being provided with means for continuously slitting the paper lengthwise, substantially as set forth.

4. A paper craping machine as claimed in 80 claim 3, wherein one of the slitting rollers, positively driven, serves as a take-off roller whence the paper-delivery reel or reels is or are driven by frictional contact, substantially as set forth.

WALTER WILLIAM COLLEY.
